UNITED STATES PATENT OFFICE

2,509,108

EVAPORATOR

John E. Pottharst, Jr., New Orleans, La.

Application June 11, 1945, Serial No. 598,773

3 Claims. (Cl. 122—34)

1

My invention relates to evaporators for use in distilling apparatus, and it comprises new and useful improvements in the same.

One of the objects of my invention is the provision of a new and improved evaporator which is adapted for assemblage with the other elements of a distilling apparatus into a compact unit requiring relatively little space. The structure and shape of the evaporators now in general use are not adapted for such purposes.

My improved evaporator is of such shape that the other elements of a distillation unit may be assembled therewith to complete a unit of such compactness as to be readily portable and to require but little space for its reception without sacrificing efficiency or output capacity.

Another object in view is the provision of an evaporator wherein the entrainment of droplets of the solution or raw liquid in the vapor produced therefrom is prevented, and thus pure water or other condensate is produced by the distilling unit of which the evaporator is an element.

Other objects in view, and other improvements in structure and in arrangement of parts will appear from the following description.

In the accompanying drawings, wherein is illustrated a practical embodiment of the principles of my present invention:

Fig. 1 is a top plan view of the evaporator, the top of the vapor chamber being partially broken away to show parts and the baffle being shown in section along the dotted line 1—1 in Fig. 2.

Fig. 2 is in part a view in front elevation, and in part in section taken along the dotted line 2—2 in Fig. 1.

Fig. 3 is a plan view of the solution chamber which forms the bottom closure of the evaporator, the chamber being shown disassembled from the evaporator for the sake of clearness.

Fig. 4 is a transverse vertical section of the evaporator taken along the dotted line 4—4 in Fig. 2 and looking toward the right in the latter view.

Fig. 5 is a partial perspective of the evaporator sectioned along the dotted line 4—4 in Fig. 2 and looking toward the left of said line in the latter view.

Fig. 6 is a plan view of the upper tube sheet.

Fig. 7 is a view in horizontal section taken along the dotted line 7—7 in Fig. 4.

Fig. 8 is a view in horizontal section taken along the dotted line 8—8 in Fig. 4.

Fig. 9 is a plan view of the lower tube sheet.

Referring to the drawings, 10 indicates the

2

vapor chamber which forms the upper portion of the evaporator and is defined by the top closure 11 and the inclosing skirt wall 12 which is supported on and is welded or otherwise attached to the upper tube sheet 13.

The chamber 10, as shown in Fig. 1, is oblong, having straight parallel front and rear walls, and semi-circular end walls.

At the rear center of the chamber the wall 12 is provided with a port 14 which is arranged for connection to a conduit for the withdrawal of vapors from the chamber.

The central portion of the tube sheet 13 is provided with an opening 15, of substantially hour-glass shape disposed transversely of the tube sheet, having arcuate side walls concentric with the semi-circular ends of the tube sheet, and straight end walls. Within the circles defined by the semi-circular ends of the tube sheet 13 and the arcuate side walls of the opening 15 the tube sheet is provided with two circular groups of tube holes 16, the individual holes of a group being closely adjacent to each other.

17 indicates the lower tube sheet having cylindrical end portions in which are provided groups of tube holes 16 corresponding in number and arrangement to the like tube holes in the upper tube sheet 13.

18 indicates the banks of vertical tubes which extend between the tube sheets and have their opposite ends rolled or welded in the holes 16 to provide tight joints.

The central portion of the lower tube sheet 17 is in the form of a relatively narrow neck 19 in the center of which is provided an opening 20 of substantially smaller dimensions than those of the opening 15 in the upper tube sheet. The side walls of the opening 20 are curved concentrically with the ends of the tube sheet.

40 Surrounding the two banks of tubes and extending between the upper and lower tube sheets are the two tubular shells 21 whose upper and lower ends are attached by tight joints, as by welding, to the tube sheets, each shell enclosing one of the two banks of tubes and forming a heating chamber for the tubes.

The lower end of the evaporator is closed by the solution chamber 22 which has a closed bottom and an upwardly extending vertical wall or skirt 23 which is flanged outwardly at the top to fit against and to be secured as by bolts to the under side of the lower tube sheet 17.

The perimetral contour of the chamber corresponds to that of the lower tube sheet.

24 indicates the front wall of the downtake,

the upper end of which is welded or otherwise attached to the underside of the upper tube sheet 13. The lower end of the wall 24 extends into and is welded to the side of the opening 20. The vertical edges 25 of the wall 24 are welded to the shells 21. The upper portion of the wall 24 is vertical but adjacent its lower portion it inclines inwardly as shown at 26, and the lower extremity 27 is vertical and extends into and is welded to the wall of the opening 20 in the lower tube sheet.

28 indicates the rear wall of the downtake which is also welded along its vertical edges to the shells 21 and at its upper end to the underside of the tube sheet 13 and at its lower end to the wall of the opening 29 in the tube sheet 17.

The upper portion of the wall 28 is vertical, its intermediate portion is inset, and the wall then is inclined downwardly and inwardly, merging into a vertical portion the lower end of which is welded to the edge of the opening 29.

Thus the upper end of the downtake, indicated generally by the numeral 29, is open through the opening 15 to the vapor chamber 10 while its reduced lower end is open to the solution chamber 22.

30 indicates a baffle which depends within and extends from side to side of the downtake, its vertical edges being welded to the shells 21.

The upper extremity of the baffle 30 is attached to or integral with the inner or rear wall of the box 31, the closed top of which is spaced from the top closure 11 of the vapor chamber 10 to permit the circulation of vapor within the latter. The side walls of the box 31 extend to and are welded to the wall 12 of the vapor chamber. 32 indicates a conduit having its inner end connected to a port in the inner wall of the box 31 and its outer end to the port 14. The bottom of the box 31 is open for the entrance of vapor from the downtake traveling upwardly in front of the baffle 30.

The upper portion of the baffle 30 is vertical as shown, forming with the rear wall 28 of the downtake a vertical passage 33 for the downward travel of vapor from the chamber 10. Below the vertical portion of the baffle is a forwardly and downwardly inclined intermediate portion of the baffle terminating in the vertically depending portion 34 which forms with the front wall 24 a passage 35 through which the vapor travels upwardly into the box 31 and thence through the conduit 32 and out through the port 15.

36 indicates a feed pipe connected to a port in the front wall 24 of the downtake for the introduction of the solution to be vaporized. 37 indicates the blowdown or withdrawal pipe for concentrated solution, said pipe extending through the front wall 24 of the downtake and extending upwardly within the lower portion of the downtake to the proper elevation to maintain the desired volume of solution in the blowdown and in the tubes 18. The level of solution in the downtake is below the lower end of the baffle.

38 indicates the condensate withdrawal pipe which connects to a manifold 39 extending between the shells 21 at the lower ends of the latter and connected to the space within the shells around and between the tubes through ports 40 in the shells.

41 indicates a manifold duct extending between the shells at the rear of the evaporator and adjacent the bottom of the shells. The extremities of the manifold connect with the in-

terior of the shells through ports 42 in the walls of the shells.

The manifold is provided with a port 43 for the introduction of vapor or steam, or both, at a temperature higher than the boiling temperature of the solution to boil the latter in the tubes 16 and evolve vapors therefrom.

During the operation of the evaporator, the impure solution is continuously supplied to the chamber 22 through the feed pipe 36 and a body of the solution is maintained in the tubes 18 and the downtake 29 at the level determined by the upper inlet end of the blowdown pipe 37 and below the lower end of the baffle 30. The vapors generated from the solution in the tubes rise into the chamber 10 and travel downward through the passage 33 in back of the baffle 30 and then reverse their direction and pass up through the passage 35 and out the box 31 and thence to the port 14.

It is a well known fact that to successfully separate the droplets of entrained liquid from a current of steam, it is usually necessary to reverse the direction of the current to reverse the direction of the flow at high velocity so that the momentum of the droplets will retard the reversal of their direction of travel with the steam, thus permitting their projection against a collecting surface.

In the case of my improved evaporator, the initial travel of the vapors in which the droplets are entrained from the vapor chamber 10 is downward through passage 33 between the baffle 33 and the rear wall 28 of the downtake, the current of vapors then abruptly reversing its path of travel around the lower extremity of the baffle into a vertically upward direction through the passage 35, the box 31, the conduit 32 and out through the port 14.

This abrupt reversal of direction of the travel of the vapors causes the droplets to be projected downwardly onto the surface of the solution in the lower end of the downtake. The condensate formed in the lower portions of the shells from the steam and hot vapor introduced through the port 43 is withdrawn by the condensate line 38.

The supply of solution to the chamber 22 is greater than that required to compensate for the evaporation of solution in the tubes, and therefore an overflow into the upper end of the blowdown 37 is continuous. Thus the concentrated solution is continuously withdrawn from and fresh solution supplied to the evaporator.

It is evident that the exterior contour of the evaporator especially recommends its employment in a distillation unit which must be compact so as to be conveniently portable and capable of being installed in a contracted space, such as in the hull of a small naval vessel.

It is further evident that by the use of my improved evaporator a better and purer character of condensate may be produced as the droplets of solution are more effectually prevented from entrainment in the vapors as the latter pass from the evaporator to the compressor.

I claim:

1. A compact evaporator consisting of a pair of spaced vertically disposed cylindrical shells closed at their ends and each having a plurality of tubes passing therethrough, means defining a common vapor chamber open to the tubes of each shell at the top of the latter, means defining a common solution chamber open to the tubes of each shell at the bottom of the latter, front and rear walls connecting said shells to complete

with said shells and chambers, a common downtake open to both of said chambers, said walls connecting said shells at substantially their great diameters at the top adjacent the vapor chamber and approaching each other adjacent the bottom forming a throat which opens to said solution chamber, an upwardly open blowdown pipe in the downtake above said throat, a downwardly open feed pipe in said throat below said blowdown pipe, a baffle connecting said shells intermediate said front and rear walls, a vapor withdrawal pipe communicating with the upper end of the downtake and on one side of said baffle, a common vapor supply duct connected to the interior of both of said shells, and a common pipe for withdrawing condensate from the interior of said shells.

2. A compact evaporator consisting of a pair of spaced vertically disposed cylindrical shells closed at their ends and each having a plurality of tubes passing therethrough, means defining a common vapor chamber open to the tubes of each shell at the top of the latter, means defining a common solution chamber open to the tubes of each shell at the bottom of the latter, front and rear walls connecting said shells to complete with said shells and chambers a common downtake open to both of said chambers, said walls connecting said shells at substantially their great diameters at the top adjacent the vapor chamber and approaching each other adjacent the bottom forming a throat which opens to said solution chamber, an upwardly open blowdown pipe in the downtake above said throat, a downwardly open feed pipe in said throat below said blowdown pipe, a baffle connecting said shells intermediate said front and rear walls, a vapor withdrawal pipe communicating with the upper end of the downtake and on one side of said baffle, a common vapor supply duct of relatively large capacity connected to the interior of both of said shells for the supply of vapor to the interior of the latter, and a common pipe of less capacity for the withdrawal of condensate from said shells.

3. A compact evaporator consisting of a pair

of spaced vertically disposed cylindrical shells closed at their ends and each having a plurality of tubes passing therethrough, means defining a common vapor chamber open to the tubes of each shell at the top of the latter, means defining a common solution chamber open to the tubes of each shell at the bottom of the latter, front and rear walls connecting said shells to complete with said shells and chambers a common downtake open to both of said chambers, said walls connecting said shells at substantially their great diameters at the top adjacent the vapor chamber and approaching each other adjacent the bottom forming a throat which opens to said solution chamber, an upwardly open blowdown pipe in the downtake above said throat, a downwardly open feed pipe in said throat below said blowdown pipe, a baffle connecting said shells intermediate said front and rear walls, a vapor withdrawal pipe communicating with the upper end of the downtake and on one side of said baffle, a third wall connecting said shells to complete with said shells and one of said first named walls a common manifold duct communicating at its opposite ends to the interior of the shells, a pipe for supplying vapor to said duct, and a fourth wall connecting said shells to complete with said shells and the other of said first named walls a common connection for the withdrawal of condensate from the interior of said shells below said duct and at a level adjacent the bottom of the latter.
